UNITED STATES PATENT OFFICE:

HANS FOERSTERLING, OF PERTH AMBOY, NEW JERSEY, ASSIGNOR TO THE ROESSLER & HASSLACHER CHEMICAL CO., OF NEW YORK, N. Y., A CORPORATION OF NEW YORK.

APPARATUS FOR MAKING STANNIC OXID.

No. 880,873.

Specification of Letters Patent.

Patented March 3, 1908.

Application filed February 23, 1905. Serial No. 246,894.

To all whom it may concern:

Be it known that I, HANS FOERSTERLING, a citizen of the United States, residing at Perth Amboy, in the State of New Jersey, 5 have invented a new and useful Apparatus for Making Stannic Oxid, of which the following is a specification.

The object of this invention is to provide an improved apparatus for the process of 10 making stannic oxid.

The invention particularly relates to the apparatus used for carrying on the continuous process described and claimed in Letters Patent, No. 780,984, granted to me, January 15 31, 1905.

This application for patent, shows, describes and claims practically the same apparatus with such improvements thereon as I have found to be of advantage in practice.

20 The apparatus comprises a melting pan arranged in a combustion furnace. This melting pan is made comparatively shallow and the metallic tin is supplied thereto. Means are provided for causing combustion 25 to melt metallic tin therein preferably by causing flame, such as that of burning gas, to play over the surface of the metallic tin in the melting pan. Means are also provided whereby a supply of air is heated and led 30 into contact with the melted tin. The air is heated previous to contacting with said tin, to a temperature such that the contacting air and tin will be above that at which the lower dark colored oxid known as stannous oxid is 35 formed. The air is first preferably heated in the furnace as hot as it can conveniently be, say up to 400 or 500 degrees centigrade and is then brought up to the specified temperature which is from 900 to 1100 degrees centi- 40 grade by its passage through said flame before it contacts with the metallic tin. The stannic oxid thus formed is removed and fresh metallic tin is supplied as the bath is depleted.

45 The apparatus and the detailed improvements thereon can be understood from the accompanying two sheets of drawings referring to which,—

Figure 1 is a sectional elevation thereof. 50 Fig. 2 is a sectional plan view taken on the line 2—2 of Fig. 1. Fig. 3 is a cross-sectional elevation taken on the line 3—3 of Fig. 1. Fig. 4 is a sectional plan view taken just in front of the melting pan. Fig. 5 is an en- 55 larged inside end view of one of the burners

and, Fig. 6 is a sectional plan view of one of the burners.

Referring to the drawings and in detail— A designates a suitable furnace which has a shallow melting pan B formed therein. A door A' is formed in the side of the furnace through which the tin may be supplied and through which the tin oxid may be removed. At the rear of the furnace are arranged a series of chambers C, C', and C². The first 60 chamber is connected with the space in the furnace inclosing the melting pan by an opening 10. The first chamber is connected with the second chamber by an opening 11, the second chamber is connected with the third 65 chamber by an opening 12, and the third chamber connects with a suitable flue 13. The openings 10, 11, 12 and the flue 13 are arranged alternately at the top and bottom of the chambers, as shown, so that the products of combustion will follow the course through said chambers indicated by arrows. An air pipe line 14, connected to a suitable 70 source of air supply as an air pump or blower, is connected to the third chamber C² and 75 said pipe is provided with a suitable valve 140 for controlling the ingress of air. The pipe line is carried down and up, transversely across the chamber C², as shown at 15 in Fig. 3 and then connects with the second chamber 80 C', where it is similarly carried down and up as at 16, and then connects with the first chamber where it is carried similarly down and up transversely as at 17. The pipe line then connects with a drum or large pipe 18 at 85 the rear of the space inclosing the melting pan. The drum 18 connects by a number of suitable pipes 19, four being shown, to a drum or a large pipe 20 at the front of the furnace. It will be noticed that the pipes 19 90 extend over the melting pan. The drum 20 connects by pipe 21 to a large pipe or drum 22 arranged above the same.

Extending out from the drum 20 are pipes 23 which connect to the burners, D four of 100 such pipes being shown as connecting to four burners. These pipes 23 are provided with suitable valves 230 as shown. Gas pipes 24 are brought up to connect also with said burners and said gas pipes are provided with 105 suitable valves 240.

The construction of one of the burners D is shown in Figs. 5 and 6. Each burner consists of a box or compartment into one end of which one of the air pipes 23 connects. The 110

box is provided with a partition 25 from which to the rear wall extends a series of short pipes 26, nine being shown. The gas pipe 24 connects to said box between said 5 partition and the rear wall.

The rear wall is provided with a series of X-shaped openings 260 arranged between the ends of the pipes 26 through which the gas can issue and as it issues, it is thoroughly 10 mixed with the air coming out through the pipes 26, whereby an extremely hot sheet of flame is produced, the combustion taking place some little distance out from the burners. The gas and air passing to each burner 15 can be regulated by the valves 230 and 240. By using a series of these burners side by side, an extremely hot sheet of flame can be caused to play over the melting pan.

The ends of the drum 20 are connected 20 with openings 27-27 which extend vertically down through side walls of the furnace and which unite in an opening 28 extending transversely between the side walls of the furnace in front of the burners D and between 25 the same and the front edge to the melting pan. The flow of air down through the vertical openings 27-27 may be controlled by suitable sliding valves or blocks 29 arranged between the vertical openings 27-30 27 and the transverse opening 28. By this arrangement it will be seen that a large proportion of the heated air will flow down through the openings 27-27 and up out of the transverse opening 28 so as to mix into 35 the sheet of flame. By this arrangement, the air will be heated to the proper temperature, 900 to 1100 degrees centigrade, so that when it contacts with the tin, stannic oxid will be formed.

40 In operation, the furnace is first brought to a very high temperature, then the initial charge of tin is melted and compressed air is supplied to the pipe line so as to act as above described. As the stannic oxid is formed, 45 it is removed by an operator with a rake through the door and as the bath is depleted, fresh tin is supplied.

The chambers C, C', and C² are provided 50 with doors through which any dust or oxid carried over the products of combustion can be removed.

By this apparatus, the continuous process of making stannic oxid can be carried on commercially with high efficiency.

55 The details and arrangements herein shown and described may be greatly varied by a skilled mechanic without departing from the scope of my invention as expressed in the claims.

60 Having fully described my invention, what I desire to secure by Letters Patent of the United States is:—

1. A furnace for making stannic oxid comprising a melting pan, means for directing 65 flames into said melting pan whereby tin

may be melted therein, and means for heating air and leading the same directly up into the flames from below at substantially right-angles to the direction of the flames previous to their contact with the tin.

2. A furnace for making stannic oxid comprising a melting pan, means for directing flames into said pan whereby tin may be melted therein, and means for heating air above the temperature at which the lower dark colored oxid is formed and leading the same directly up into the flames from below previous to their contact with the tin. 70

75 3. A furnace for making stannic oxid comprising a melting pan, means for directing flames horizontally over the pan, and means for introducing air directly upward into the flame before it contacts with the tin. 80

85 4. A furnace comprising a melting pan, means for directing a wide horizontal flame of burning gas over the melting pan, means for initially heating air, and means for introducing the heated air directly upward into the flame from below entirely across said flame before the flame enters said pan. 90

95 5. A furnace for making stannic oxid, comprising a melting pan, means for directing burning gas over the melting pan, means for heating air, means for mixing part of said heated air with the gas for the purpose of combustion, and means for introducing the rest of said air directly under and into the flame. 100

105 6. A furnace for making stannic oxid, comprising a melting pan, means for directing burning gas over said melting pan, chambers beyond said pan and connected to each other and the melting chamber, air pipes in said chambers for utilizing the heat in said chambers for initially heating air, means for mixing part of the heated air with the gas, and means for directing the rest of the heated air into the flame before it contacts with the metal. 110

115 7. A furnace comprising a melting pan, means for directing burning gas over said melting pan, a series of connected chambers beyond said pan and connected to the exit end of the melting chamber, a pipe extending transversely in each of said chambers, and means connected to this pipe for directing the air heated in said pipe line into the flame before it contacts with the metal. 120

125 8. A furnace comprising a melting pan, means for directing burning gas over said pan, a series of connected chambers beyond said pan, a pipe line extending successively through said chambers and over the melting pan, and means for leading air heated thereinto into contact with the melted metal.

9. A furnace, comprising a melting pan, means for directing burning gas over said pan, chambers beyond said pan, a pipe line extending through said chambers and over the melting pan, and means for leading the 130

air heated therein down at the side of the furnace and then up into the flame.

10. A furnace, comprising a melting pan, burners for directing burning gas over said 5 pan, a pipe line in said furnace for heating air, and connections to said pipe line arranged so that part of the air heated therein will be directed to mix with the gas before combustion, and so that the rest of said air 10 will be introduced directly under and into the flame before it contacts with the metal.

11. A furnace, comprising a melting pan, a series of gas burners arranged in front of said pan for directing burning gas thereover, 15 chambers at the rear of said pan, a pipe line extending from said chambers and over said melting pan, means for directing part of the heated air to said burners, and regulable means for directing the rest of said heated 20 air to mix into the flame from the underside before it contacts with the metal.

12. A furnace of the class described, consisting of a furnace structure having a melting pan, a burner in its front wall arranged to 25 direct its flames into said melting pan, a transverse chamber formed in the furnace structure and opening into the combustion chamber between the melting pan and the burner and under the flames, vertical air passages 30 in the furnace structure connected to said transverse passage, a transverse heating drum in the combustion chamber and connected at its ends to said vertical air passages, a pipe line extending forward over the 35 melting pan and connected to said transverse heating drum, valved pipes leading from said heating drum to the burner, and means for supplying fuel to the burner, substantially as set forth.

40 13. A furnace comprising a melting pan, a burner constructed to project flames into the melting pan, means for conducting a supply of air into said flame, and means for leading a part of said supply of air directly upward 45 into the flames at a point between the burner and the melting pan.

14. A furnace comprising a melting pan, a burner for directing flames into the melting pan, and means for leading a supply of air 50 upward into the flames, said means consisting of an air chamber extending across the front walls of the furnace at a point between the burner and the melting pan and having an open top under the path of said flame.

55 15. In a furnace, the combination of a melting pan, a series of chambers at one end

of said melting pan through which the products of combustion are adapted to pass, said chambers opening into each other and their openings being in staggered relation with 60 each other, a burner located at the discharge end of the melting pan, means for feeding a fluid fuel to said burner, a pipe connected with a source of compressed air passing in turn through each of said chambers and over 65 the top of the melting pan and through the front wall of the furnace, said pipe passing outside the furnace and into said burner, and having means outside the furnace whereby the flow of air to the pipe may be regulated. 70

16. In a furnace, the combination of a melting pan, a series of chambers at one end of said melting pan through which the products of combustion are adapted to pass, said chambers opening into each other and their 75 openings being in staggered relation with each other, a burner located at the discharge end of the melting pan, means for feeding a fluid fuel to said burner, a pipe connected with the source of compressed air passing in 80 turn through each of said chambers and over the top of the melting pan and through the front wall of the furnace, said pipe passing outside the furnace and into said burner, and having means outside the furnace whereby 85 the flow of air to the pipe may be regulated, the furnace having a passage in its front side under the flame from the burner, means for conducting a part of the air from said pipe into said passage, and means for conducting 90 the air from said passage into the flame before it strikes the metal.

17. In a furnace, the combination of a melting pan, a burner at one end thereof, a pipe for conducting air above said melting 95 pan, whereby the air may be heated, said pipe extending out of the furnace and into the burner, said furnace having a passage below the front end thereof, means for conducting part of the air from said pipe into 100 said passage, means for conducting air from said passage into the flame before it strikes the burner, and means for regulating the last named conducting means.

In testimony whereof I have hereunto set 105 my hand, in the presence of two subscribing witnesses.

HANS FOERSTERLING.
